UNITED STATES PATENT OFFICE.

EDWARD PHILLIPS, OF MOUNT FOREST, ONTARIO, ASSIGNOR OF ONE-HALF
TO CHARLES LEWIS SMITH AND JOSEPH DIXON SMITH, BOTH OF VARNA,
CANADA.

LETTER OR DOCUMENT FILE.

SPECIFICATION forming part of Letters Patent No. 415,056, dated November 12, 1889.

Application filed February 23, 1889. Serial No. 300,941. (No model.) Patented in Canada October 30, 1888, No. 30,061.

To all whom it may concern:

Be it known that I, EDWARD PHILLIPS, of the town of Mount Forest, in the county of Wellington, in the Province of Ontario, Canada, have invented a certain new and Improved Letter or Document File, of which the following is a specification.

The object of the invention is to design a simple letter or document file in which letters or documents may be neatly arranged in drawers designed to fall out of the cabinet by their own gravity, simple appliances being provided by which the documents are clamped in position and the drawers locked when closed; and it consists, essentially, of a cabinet having letter or document drawers supported on slanting shelves arranged in the cabinet, the sides of each drawer being notched to receive a clamp hinged on the side of the cabinet opposite to each drawer, suitable appliances being arranged in connection with the drawers for holding the letters or documents in position, and with the clamp for operating the latter, the whole being constructed and arranged substantially as hereinafter more particularly explained.

The drawing represents a perspective side section of a cabinet provided with my improvement.

In the drawing, A represents the cabinet, and B shelves or supports arranged within the cabinet so as to carry each drawer at a sufficient angle to permit of it falling, when unlocked, out of the cabinet by its own gravity. The sides of each drawer C have notches cut in them, in which the hinged clamp D fits when the drawer is closed, as indicated in the upper portion of the figure shown.

E is a chain or cord connected at one end to the back of the clamp D, and being fastened at its other end to a drum a, journaled in a bracket attached to the bottom of the shelf B. The drum a can only be operated by a key b inserted in a key-hole made in the face of the cabinet. By turning the key b the drum a is revolved, and the clamp D, through the cord or chain E, is lifted out of

the notch made in the side of the drawer C, when the said drawer will by gravity fall out of the cabinet until the hook F, projecting from its bottom, engages with a notch formed in the shelf B, or on the front of the cabinet. A cord or strap G connects the inner end of the drawer C to the shelf B, so as to hold the drawer at a proper angle when it has fallen out of the cabinet, as indicated by the position of the lower drawer shown in the drawing. A spring H is connected to the inside of the cabinet A, and is designed to press upon the top of the clamp D, so as to hold the said clamp down in its notch when not drawn upon by the cord E.

With the view of holding the letters or documents in the drawer, I provide a board I, which is held in position by the spiral spring J, so that the board may be adjusted to suit the different thicknesses of the documents.

What I claim as my invention is—

1. A cabinet having letter or document drawers supported on slanting shelves arranged in the cabinet, in combination with a hinged clamp arranged inside the cabinet to engage with a notch or notches made in the side or sides of the drawer, substantially as and for the purpose specified.

2. A cabinet having letter or document drawers supported on slanting shelves arranged in the cabinet, in combination with a hinged clamp arranged inside the cabinet to engage with a notch or notches made in the side or sides of the drawer, and a cord attached to the hinged clamp and arranged substantially as and for the purpose specified.

3. A cabinet having letter or document drawers supported on slanting shelves arranged in the cabinet, in combination with the hook F on the under side of said drawer, and cord or strap G, connected to said shelf and to the under side of said drawer, substantially as and for the purpose specified.

4. A cabinet having letter or document drawers supported on slanting shelves ar-

ranged in the cabinet, in combination with a hinged clamp arranged inside the cabinet to engage with a notch or notches made in the side or sides of the drawer, a spring arranged to act against the clamp to hold it in the notch, and a chain or cord attached to the hinged clamp to raise the said clamp,

substantially as and for the purpose specified.

Toronto, February 4, 1889.

EDWARD PHILLIPS.

In presence of—

CHARLES C. BALDWIN,
CHAS. H. RICHES.
